UNITED STATES PATENT OFFICE.

HARRY S. HART, OF CHICAGO, ILLINOIS, ASSIGNOR TO RODGER BALLAST CAR COMPANY, OF CHICAGO, ILLINOIS, A CORPORATION OF MAINE.

CONVERTIBLE FREIGHT-CAR.

1,198,725.

Specification of Letters Patent. Patented Sept. 19, 1916.

Application filed March 28, 1914. Serial No. 827,921.

To all whom it may concern:

Be it known that I, HARRY S. HART, a citizen of the United States, residing at Chicago, in the county of Cook and State of Illinois, have invented certain new and useful Improvements in Convertible Freight Cars, of which the following is a specification.

My invention relates in general to freight cars and more particularly to a combined ballast and general service car.

Heretofore freight cars convertible into either flat bottom gondola cars or center dump hopper cars, particularly adapted for ballasting, have been extensively used with great success. Numerous types of side dump flat bottom cars have also been built and their adaptability for carrying various kinds of freight has led to their being known as general service cars. So far as I am aware, however, no cars have heretofore been constructed capable of satisfactory use for all of the purposes for which the above mentioned convertible cars and the side dump general service cars are separately adapted.

The primary object of my invention is to provide a combination freight car which may be readily converted into a flat bottom gondola car, or into a center dump hopper car or into a flat bottom side dump general service car.

A further object of my invention is to provide a combination freight car adapted for a variety of uses which will be comparatively simple in construction, convenient in adjustment, and efficient in use.

My invention will be more fully disclosed hereinafter with reference to the accompanying drawings, in which the same is illustrated as embodied in a convenient and practical form and in which—

Figure 1 is a plan view of one of the end portions of a car embodying my invention; Fig. 2 a vertical section on line 2, 2 Fig. 1; Fig. 3 an enlarged detail view of the means for adjustably supporting one of the end walls; Fig. 4 a cross sectional view, the parts being arranged to form a center dump hopper car; Fig. 5 a view similar to Fig. 4, the parts being arranged to form a flat bottom side dump general service car; Fig. 6 a detail view showing a structural modification of the means for supporting the central ex-

tensions of the doors; Fig. 7 an enlarged detail longitudinal sectional view on line 7, 7, 55 Fig. 4 of the car when arranged as a center dump hopper car; Fig. 8 an enlarged detail plan view of a portion of the car when arranged as a general service car; and Fig. 9 a cross sectional view on line 9, 9, Fig. 8. 60

Similar reference characters are used to designate similar parts in the several figures of the drawings.

Reference letter A designates one of the end sills, B one of the bolsters, and D one 65 of the cross bearers, or transverse members of the underframe, which are located intermediate of the bolsters. Preferably the car floor is divided into eight sections by means of the end sills, the bolsters, and five cross 70 bearers, such as D.

C indicates draft beams which extend outwardly from each of the bolsters to the adjacent end sill.

E', E² designate the sides of the car, 75 which is preferably of the gondola type, the sides being rigidly secured to the transverse members of the underframe by means of stakes E.

E² designate beams which extend longitudinally of the car along the inner surfaces of the car sides immediately above the transverse underframe members, and which serve to add rigidity to the car frame and to the connection therewith of the sides. 80

F designates one of the end walls which is preferably made longitudinally adjustable so as to occupy a position either at the end of the car or in a plane above the cross bearer D nearest that end of the car. In 90 order to securely support the end wall F in either of its positions a vertical central stake f is secured to the outer surface thereof which extends slightly below the lower edge of the end wall and is adapted to be received 95 within a socket c', or c², formed in the floor plate c above the draft beams C. The top of each end wall F is secured between the side walls in either of its positions by means of bolts F' and F², one located at each side 100 of the end wall and adapted to detachably engage the top of the side walls. By reference to Fig. 3 it will be seen that each of the bolts F' and F² is supported by spaced brackets f' and f² secured to each upper side 105 edge of the end wall, and extends through

a hole in the adjacent Z-bar e' along the top of the adjacent side of the car. A nut f^3 engages the end of each of the bolts which projects through the adjacent side wall.

- 5 The inner end of each bolt is bent downwardly, as shown in Figs. 4 and 5, so as to overlie the inner one of the supporting brackets f' . A pin f^4 extends through each bolt intermediate of the supporting brackets and serves as a stop to limit the inward movement of the bolt when being disengaged from the car side. It will be observed by reference to Figs. 4 and 5 that the portions of each end wall on which the bolts 10 are mounted overlie the projecting horizontal flanges of the Z-beams e' along the upper edges of the car sides.

The two bolsters are rigidly connected by longitudinal beams which pass through 20 and are rigidly connected to the cross bearers D. These longitudinal beams, or sills, are preferably located a considerable distance inwardly from the car sides, and below the plane of the car floor, as shown in 25 Figs. 4 and 5, in which G' and G^2 designate the said longitudinal sills. Each of the sills may be conveniently formed of two superposed Z-bars arranged with their upper and lower horizontal flanges extending inwardly 30 and with their overlying horizontal flanges extending outwardly. Flanged plates g' and g^2 are secured to the inwardly projecting upper flanges of the sills G' and G^2 and extend downwardly in a converging direction. These plates are supported adjacent 35 their lower edges by longitudinal flanged beams g^3 and g^4 which are interposed between the said plates and the inner surfaces of the lower Z-beams forming the sills G' 40 and G^2 . A wall G^3 extends downwardly below the lower edge of the plate g' so as to form a continuation thereof, such wall being conveniently formed as part of the flanged beam g^3 . The lower end of the wall G^3 is 45 connected by suitable braces G^5 with the several cross bearers D. The wall G^3 extends continuously from one of the outer cross bearers D to the other outer cross bearer D so as to occupy the space intermediate of the trucks. Pivotaly supported 50 by suitable brackets secured within the flanged longitudinal beam g^4 is a door G of a length equal to that of the wall G^3 . To the lower edge of the door G are secured 55 chains H by any suitable fastening device, such for instance as eye-bolts h, such chains being connected to a longitudinal shaft H' journaled beneath the cross bearers D by suitable brackets h'. The plates g' and g^2 , 60 together with the inclined wall G^3 and door G, form a central hopper extending longitudinally of the car intermediate of the end cross bearers D.

The cross bearers D are cut away to receive 65 the longitudinal sills composed of the su-

perposed Z-bars, the flanged plates g' , g^2 , and the interposed flanged beams g^3 , g^4 , as clearly shown in Figs. 4 and 5. An angle bar d extends beneath the longitudinal sills and vertically aligns with each cross bearer 70 D to which it is rigidly connected.

D' and D^2 designate gusset plates which rigidly secure the ends of each angle bar d to the adjacent portions of the overlying cross bearer D. The gusset plates fit within 75 the outer surfaces of the lower Z-bars of the longitudinal sills.

d' and d^2 designate angles which fit within the outer surfaces of the upper Z-bars of the longitudinal sills and are riveted to each 80 cross bearer D. The upper ends of the connecting angles d' , d^2 are riveted to the ends of a transverse angle bar g , which lies on the opposite side of the cross bearer D and extends immediately above the upper horizontal flanges of the plates g' , g^2 as clearly 85 shown in Figs. 4, 5, 7 and 9. The portion D^3 of each cross bearer D intermediate of the flanged plates g' and g^2 , converges downwardly and is provided with a flange d^3 90 which overlies and is secured to the horizontal flange of the underlying transverse angle bar d .

Floor sections K' and K^2 are provided along the opposite sides of the car intermediate of the end cross bearers D, one of such floor sections being located at each side of the longitudinal center of the car between adjacent cross bearers D. The lower edge of each floor section K' and K^2 is provided 100 with longitudinally projecting trunnions k at its sides, each of which is preferably provided with an anti-friction roller K. The rollers K are adapted to engage seats l' and l^2 formed adjacent the ends of brackets 105 L' , L^2 . Two of such brackets are secured to the surfaces of the cross bearers D in positions to be engaged by the rollers on the trunnions at the lower edge of each floor section, as will be readily understood by reference to Fig. 7. When the rollers on the trunnions engage the outer seats l' in the brackets L' , L^2 , the floor sections are supported in inclined positions as shown in 110 Fig. 4, the outer upper edges of the floor sections in such positions resting against the inner surface of the car sides.

Inasmuch as the floor sections are of a length to fit between adjacent cross bearers D there are necessarily spaces between adjacent sections when they are in the inclined positions shown in Fig. 4. In order to cover such spaces a plate M is provided between the adjacent floor sections, such plate being provided at its lower end with a hinge member m' which surrounds the trunnion k on one of the adjacent floor sections, as will be readily understood by reference to Figs. 7 and 8. The upper ends of the plates M are retained in close contact with the sides of 115 120 125 130

the adjacent floor sections, which they overlie, by means of oscillatory clamping devices M' pivotally connected to the car sides.

- Secured along the lower edge of each of 5 the floor sections K' and K^2 is an extension plate N provided at its sides with hinge members n which surround the trunnions k on the floor section to which it is thereby pivotally connected. The edge of each plate 10 N , opposite to that which is pivotally connected to the adjacent floor section, is provided with bolts N' which are supported in keepers n' at the sides of each plate N . The bolts N' are adapted to be projected beyond 15 the side edges of the extension plate N on which they are mounted, and to overlie the adjacent side edges of cover plates q rigidly secured to the upper central portions of the flanges of the cross bearers D , shown in 20 Figs. 1, 5 and 8, when the parts of the car are adjusted to form a flat bottom general service car, in a manner hereinafter more fully described.

The floor sections in each end of the car 25 on opposite sides of the bolster are formed by drop doors O' and O^2 , two of such doors being located on each side of the draft beams C .

Extending longitudinally of the car beneath the floor level are rotary and bodily 30 movable shafts P' and P^2 , such shafts extending through upwardly and outwardly inclined slots formed in the cross bearers, bolsters, and end sills. The shafts P' and 35 P^2 are provided with sprocket wheels p' and p^2 which engage sprocket pins q' and q^2 supported adjacent the lower edges of the inclined slots in the transverse members of the underframe. The ends of the shafts P' and 40 P^2 which project through the end sills are provided with suitable pawl and ratchet mechanism R' and R^2 for rotating the shafts and thereby causing them to travel outwardly and upwardly, or inwardly and 45 downwardly, within the slots in the transverse members of the underframe through which they pass.

Pivotally connected to the inner surfaces 50 of the car sides immediately above the ends of the cross bearers D are floor plates S' and S^2 , which may be swung upwardly into the position shown in Fig. 4 when the car is arranged as a center dump hopper car, or may be swung downwardly to overlie the outer 55 edges of the floor sections when the car is arranged as a general service car, as shown in Fig. 5.

The manner of using and operation of 60 my improved combination car are as follows: When the car is to be used for purposes for which a center dump hopper car is best adapted, as for instance ballasting, the floor sections K' and K^2 are placed in the inclined position shown in Figs. 4 and 65 7, the lower edges of the floor sections be-

ing supported by means of the rollers on the trunnions engaging within the outer seats l' of the supporting brackets L' and L^2 and the upper edges of the floor section being retained against the inner surfaces of 70 the sides by means of the clamps M' , which engage the upper ends of the filler plates M . Inasmuch as each filler plate M is pivotally connected at its lower end to only one of the adjacent floor sections, it is obvious that the floor sections may be separately placed in their inclined positions, one of the filler plates being coincidentally placed in such inclined position with the door section to which it is connected. The 80 floor extension plates N overlie at their lower edges the inclined plates g' and g^2 along the upper edges of the hopper. The end walls F are moved inwardly and secured in planes above the outer cross bearers D so as to serve as end walls for the upper portion of the hopper formed by the floor sections K' , K^2 . The lading may be dumped at the center of the car by permitting the chains H to unwind from the shaft 85 H' and thereby allow the door G to swing away from the inclined wall G^3 . The hopper may be again closed by winding the chains H upon the shaft H' so as to swing the door into the closed position shown in 90 Fig. 4.

When it is desired to use the car for purposes for which a flat bottom, side dump car is best adapted, the floor sections K' , K^2 are 95 separately moved inwardly at their lower edges until the rollers on their trunnions are seated within the inner recesses l' in the brackets L' and L^2 . The floor sections are then supported adjacent their outer edges by means of the shafts P' and P^2 , as clearly 100 shown in Fig. 5. In this position of the floor sections the filler plates M rest upon the top flanges of the cross bearers D and lie intermediate of the car sides and the central fixed cover plates d . The extension 105 plates N are swung upwardly into horizontal alignment with the floor level and the bolts N' are forced outwardly to overlie the fixed cover plates q on the adjacent cross bearers D , thereby supporting such extension plates in positions to fill the space intermediate of the inner edges of the two series of floor sections K' and K^2 . The end walls F are then adjusted outwardly to the 110 ends of the car sides, as shown in Figs. 1 and 2.

In order to permit the floor sections to drop in order to discharge the lading, the shafts P' and P^2 are moved inwardly and 115 downwardly within the surrounding slots within the transverse members of the underframe, thereby permitting the doors to swing downwardly to the position shown in dotted lines in Fig. 5. The floor sections 120 may be again raised into closed positions 125 130

by causing the shafts P' and P^2 to move upwardly and outwardly, relatively to the surrounding slots, into the position shown in full lines in Fig. 5 in which they support the doors firmly in position flush with the floor level. The hinged floor strips S' and S^2 overlie the outer edges of the floor sections, while the transverse filler plates M overlie the side edges of the adjacent floor sections. Coincidently with the operation of the floor sections K' , K^2 , the drop doors O' and O^2 are also operated, through the medium of the shafts P' and P^2 . In lieu of supporting the inner edges of the floor extension plates N by means of the bolts N' , brackets T may be secured to the cross bearers D upon which the inner edges of said floor extension plates may rest when the inner edges of the floor sections are moved inwardly to the positions they occupy when the car is to serve as a general service car. This modification is illustrated in Fig. 6.

From the foregoing description it will be seen that I have invented an improved combination freight car which may be conveniently converted either into a center dump hopper car, or into a flat side dump general service car.

It will be further observed that in my invention when the car is adjusted to serve as a general service car it will comprise drop floor doors on the opposite sides of the longitudinal center thereof extending from end to end of the car, while when the car is adjusted to serve as a center dump hopper car only the portion thereof intermediate of the trucks will be utilized so as to efficiently serve as a ballast car.

It will also be evident that I have invented an improved under-frame structure for freight cars comprising novel forms of longitudinal sills extending through cross bearers also of novel construction.

While I have described my invention with more or less minuteness and as being embodied in certain precise forms, yet it will be understood that I do not desire to limit myself thereto unduly, or any more than is pointed out in the claims. On the contrary, I contemplate all proper changes in form, construction, and arrangement, the omission of immaterial parts, and the substitution of equivalents, as circumstances may suggest or necessity render expedient.

55 I claim:

1. In a combination freight car, the combination with bodily displaceable floor sections at the opposite sides of the longitudinal center-line of the car, means for supporting said sections in inclined positions converging downwardly from the car sides, a structure intermediate of the inner edges of said sections to control the central discharge of lading, means for pivotally supporting the inner edges of said sections

when they are moved inwardly to serve as drop floor doors, and means for supporting said sections in, lowering them from, and raising them to substantially the horizontal plane of the car floor.

70

2. In a freight car, the combination with a plurality of bodily displaceable longitudinal floor sections on the opposite sides of the longitudinal center-line of the car, of means for supporting said sections in downwardly converging inclined position, means for pivotally supporting the inner edges of said sections when adjusted inwardly to form portions of a flat floor, and means for supporting said sections in, lowering them from, and raising them into horizontal alignment with the level of the car floor.

75

3. In a combination freight car, the combination with a longitudinal hopper below the floor level, of bodily displaceable floor sections at the opposite sides of the longitudinal center-line of the car, means for supporting said sections in inclined position to form continuations of said hopper, means for pivotally supporting the inner edges of said sections when they serve as drop floor doors, and means for raising and lowering said sections into and out of alignment with the car floor.

80

4. In a combination freight car, the combination with a longitudinal hopper below the floor level, of laterally movable floor sections at the opposite sides of the longitudinal center-line of the car, means for supporting said sections in inclined position to form continuations of said hopper, means for pivotally supporting the inner edges of said sections when they serve as drop floor doors, means for raising and lowering said sections into and out of alignment with the car floor.

85

100

5. In a combination freight car, the combination with a hopper below the floor level, of a plurality of laterally movable floor sections on the opposite sides of the longitudinal center-line of the car intermediate of the cross bearers, means for supporting said sections in inclined positions to form continuations of said hopper, means for pivotally supporting the inner edges of said sections when they are moved inwardly to form drop floor doors, movable filler strips to close the space between the side edges of adjacent sections, said strips adapted to overlie the cross bearers when the sections serve as floor doors, and means for raising and lowering said sections into and out of alignment with the car floor.

105

115

6. In a combination freight car, the com-

110

120

125

130

- bination with a hopper below the floor level, of a plurality of laterally movable floor sections on the opposite sides of the longitudinal center-line of the car intermediate of the cross bearers, means for supporting said sections in inclined positions to form continuations of said hopper, means for pivotally supporting the inner edges of said sections when they are moved inwardly to form drop floor doors, movable filler strips to close the space between the side edges of adjacent sections, said strips adapted to overlie the cross bearers when the sections serve as floor doors, a plate pivotally connected with the inner edge of each of said sections, means for supporting said plates adjacent the longitudinal center of the car to form central floor strips intermediate of said sections when the latter serve as drop floor doors, and means for raising and lowering said sections into and out of alinement with the car floor.
7. In a convertible freight car, the combination with laterally displaceable floor sections on the opposite sides of the longitudinal center-line of the car, pairs of transversely spaced bearings fixed to the cross bearers, projections at each side of the inner edges of said sections adapted to engage the outer bearings of said pairs to support said sections in inclined downwardly converging positions or to engage the inner bearings of said pairs to pivotally support the inner edges of said sections for the latter to serve as drop floor doors, and means engaging said sections to raise and lower the same to and from the level of the car floor.
8. In a convertible freight car, the combination with laterally displaceable floor sections on the opposite sides of the longitudinal center-line of the car, bearings fixed to the cross bearers, projections at each side of the inner edges of said sections adapted to engage said bearings to support said sections in inclined downwardly converging positions or to pivotally support the inner edges of said sections for the latter to serve as drop floor doors, a plate pivotally connected with the inner edge of each of said sections, means for supporting said plates adjacent the longitudinal center line of the car to form floor strips intermediate of said sections when the latter serve as drop floor doors, and means engaging said sections to raise and lower the same to and from the level of the car floor.
9. In a convertible freight car, the combination with laterally movable floor sections on the opposite sides of the longitudinal center-line of the car, bearings fixed to the cross bearer, projections at each side of the inner edges of said sections adapted to engage said bearings to support said sections in inclined downwardly converging positions or to pivotally support the inner edges of said sections for the latter to serve as drop floor doors, a plate pivotally connected with the inner edge of each of said sections, means for supporting said plates adjacent the longitudinal center line of the car to form floor strips intermediate of said sections when the latter serve as drop floor doors, and means engaging said sections to raise and lower the same to and from the level of the car floor.
10. In a combination freight car, the combination with laterally movable sections at the opposite sides of the longitudinal center-line of the car intermediate of the cross bearers, bearings fixed to the cross bearings, projections at each side of the inner edges of said sections adapted to engage said bearings to support said sections in inclined downwardly converging position or to pivotally support the inner edges of said sections for the latter to serve as drop floor doors, movable filler strips to close the spaces between the side edges of adjacent sections when the latter are supported in inclined positions and to overlie the cross bearers when the sections serve as drop floor doors, a plate pivotally connected with the inner edge of each of said sections, means for supporting said plates adjacent the longitudinal center-line of the car to form floor strips intermediate of said sections when the latter serve as drop floor doors, and means for raising and lowering said sections to and from the level of the car floor.
11. In a combination freight car comprising sides and longitudinally adjustable end walls, series of drop floor doors extending from end to end of the car and pivoted at their inner edges adjacent the longitudinal center-line of the car, means for raising and lowering said doors into and out of alinement with the car floor, means for supporting a plurality of the center doors in inclined downwardly converging positions to form a center dump hopper, means intermediate of the inner edges of said center doors to control the central discharge of lading, and means for supporting the end walls in position to form the ends of said hopper.
12. In a convertible freight car, the combination with a plurality of laterally movable sections on the opposite sides of the longitudinal center-line of the car occupying the spaces between the cross bearers, bearings fixed to the cross bearers, trunnions at each side of the inner edges of said sections adapted to engage said bearings to support said sections in downwardly converging inclined positions or to pivotally support said sections for the latter to serve as drop floor doors, a plate pivotally connected with the inner edge of each of said sections, means for supporting said plates adjacent the longitudinal center-line of the car to form floor strips intermediate of said sections when the latter serve as drop floor doors, and means engaging said sections to raise and lower the same to and from the level of the car floor.

support the inner edges of said sections for the latter to serve as drop floor doors, movable filler strips to close the spaces between the side edges of adjacent sections when the 5 latter are supported in inclined position, each of said sections being pivotally connected to the trunnion on one of the adjacent sections, a plate pivotally connected with the inner edge of each of said sections 10 through the medium of said trunnions, means for supporting said plates adjacent the longitudinal center line of the car to form floor strips intermediate of the sections when the latter serve as drop floor 15 doors, and means for raising and lowering said sections into and out of alignment with the floor level.

13. A car comprising a floor formed of sections having a sliding and swinging 20 movement transversely of the car, and supporting brackets secured to the car frame and having a plurality of seats to support the inner edges of said sections in different longitudinal planes.

25 14. A car comprising a floor formed of sections having a sliding and a swinging movement transversely of the car, and longitudinal plates movable into horizontal position to overlie the outer edges of said sections, and movable into vertical positions to 30 permit movement of the outer edges of said sections.

15. A car comprising fixed side walls and a floor formed of sections having a sliding 35 and a swinging movement transversely of the car, and longitudinal plates hinged at their outer edges adjacent the bottom of the inner surfaces of the side walls adapted to lie in horizontal planes to overlie the outer 40 edges of said sections and to be swung into vertical positions to permit the upward movement of the outer edges of said sections.

45 16. In a combination freight car, the combination with a longitudinal stationary hopper below the floor level, of bodily displaceable floor sections on the opposite sides of the longitudinal center line of the car,

means for supporting said sections in inclined position to form continuations of said hopper, means for pivotally supporting 50 the inner edges of said sections when they serve as drop floor doors, and means for raising and lowering said sections.

17. In a combination freight car, the combination with a longitudinal hopper below 55 the floor level, bodily displaceable floor sections on the opposite sides of the longitudinal center line of the car, means for supporting the inner edges of said sections in the planes of the walls of said hopper for 60 said sections to form continuations of said hopper, means located nearer the center line of the car than said first means for pivotally supporting the inner edges of said sections when they serve as drop floor doors, and 65 means for raising and lowering said sections.

18. In a combination freight car, the combination with a longitudinal permanent hopper, the top of which terminates in a 70 horizontal plane below the floor level, of bodily displaceable floor sections on the opposite sides of the longitudinal center line of the car, means for supporting said sections in inclined position to form continuations of said hopper, means for pivotally supporting the inner edges of said sections when they serve as drop floor doors, means for raising and lowering said sections, longitudinal center plates, means for supporting 75 said center plates between the inner edges of said sections when the latter serve as drop floor doors, and means for supporting said plates in inclined positions between the top edges of the walls of the hopper and 80 the inner edges of said sections when the latter serve as continuations of said hopper.

In testimony whereof, I have subscribed my name.

HARRY S. HART.
